Primary Examiner — Angela J Lee*Assistant Examiner* — Shawn T Gingrich(74) *Attorney, Agent, or Firm* — Cozen O'Connor(57) **CLAIM**

The ornamental design for a switching device, as shown and described.

DESCRIPTION

FIG. 1 is a front elevational view of a switching device showing our new design;

FIG. 2 is a rear elevational view thereof;

FIG. 3 is a top plan view thereof;

FIG. 4 is a bottom plan view thereof;

FIG. 5 is a right-side elevation view thereof;

FIG. 6 is left-side elevation view thereof; and,

FIG. 7 is a front, top and left-side perspective view thereof.

The broken line portions of the drawing figures are included to show subject matter that form no part of the claimed design.
